UNITED STATES PATENT OFFICE

131,057

DESIGN FOR A TOOL RACK

Charles G. Dowd, Baltimore, Md.

Application August 9, 1941, Serial No. 102,775

Term of patent 3½ years

To all whom it may concern:

Be it known that I, Charles G. Dowd, a citizen of the United States, stationed at Holabird Quartermaster Depot, Baltimore, Maryland, residing at Baltimore, in the State of Maryland, have invented a new, original and ornamental Design for a Tool Rack, of which the following is a specification, reference being had to the accompanying drawing, forming a part thereof.

Fig. 1 is a top plan view of a tool rack, showing my design;

Fig. 2 is a side elevational view thereof;
Fig. 3 is a left end elevational view of Fig. 1;
and

Fig. 4 is a right end elevational view of Fig. 1.
I claim:

The ornamental design for a tool rack, as shown.

CHARLES G. DOWD.
